UNITED STATES PATENT OFFICE

2,561,872

KNEE PROTECTOR FOR OVERALLS AND OTHER GARMENTS

Joseph Krinick, Brooklyn, N. Y.

Application February 15, 1950, Serial No. 144,259

9 Claims. (Cl. 2—23)

This invention relates to new and useful improvements in knee protectors for overalls, dungarees, gardener's trousers, miscellaneous work clothes, children's play clothes, and the like; and, more particularly, the aim is to provide a novel and valuable knee protector characterized by extreme simplicity of construction, yet of highly efficient behavior when in use on a garment while being worn in that during walking there is no interference with a free stride and during kneeling a soft perfectly cushioning protection is afforded.

A feature of the invention is that the new protector is in the main a single pad of sponge or foam rubber or similar padding generally, as now preferred, rectangular in outline, and of uniform thickness all over except at certain special points, so that the pad may be cut with minimum waste of material from a sheet of rubber material of standard thickness. More specifically the outline of the pad is preferably oblongovate, so as to present four rounded corners adjacent to each of which one of said points is located; and at each of said points a fastening instrumentality is carried by the pad whereby at all said points the pad may be readily yet securely attached to the front of a trouser leg or the like at precisely the position to insure that when a kneeling posture is assumed said pad must naturally become interposed between the surface kneeled on and a knee-joint of the kneeling person.

Another feature of the invention resides in certain provisions made in connection with the manner of securement of said fastening instrumentalities to the pad, whereby with said instrumentalities inclusive of such a hard and unyielding material as a metallic one, the metal thus necessarily incorporated in the body of the pad is so placed in the pad material that there is no possibility of said metal being interposed between the ground and the knee of the kneeling person in a way to prevent immediately adjacent portions of the pad from acting with that adequate cushioning effect essential to perfect comfort during a prolonged period of kneeling even on a pebbly or similarly non-smooth damp or wet piece of ground—even when, as now preferred, each such metal instrumentality is inclusive of an elongate more or less rod-like portion passing through the pad in substantially the direction of its thickness.

A further feature of the invention is the provision, in combination with said fastening instrumentalities, these always carried by the pad,

of coacting fastening instrumentalities carried by the trousers or the like, whereby the pad may be readily detachably yet securely connected to said trouser leg and in any selected one of a plurality of locations spaced along the length of said leg.

Still a further feature of the invention is the provision, in combination with a pad as above, and in combination with fastening instrumentalities as above, of a special carrying means for the said coacting fastening instrumentalities, that is, for the fastening instrumentalities to be permanently carried by a trouser leg or the like; with said means of such a nature that, without the aid of stitching, stapling, riveting, pinning or the like, said carrying means may be permanently yet easily bonded to a garment, as at the front of a trouser legs of such garment, at a placement fixed along the length of said leg so relative to the length thereof and so relative to the location of the knee-joint of the wearer relative to his leg length, that the pad when attached will itself be at an ideal placement.

Still another feature of the invention, in a now favored way of carrying out the same, is the equipment of said special carrying means with a plurality of sets of said coacting fastening instrumentalities, with one set higher than the other on said carrying means when disposed as it would be placed on a trouser leg or the like; thus to allow of the pad at different times to become changed in position relative to the length of said trouser leg, despite the fact that the special carrying means is, as already stated, permanently bonded to said leg at a definite placement along its length.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a frontal perspective view, showing a pair of trousers, on each of the legs of which, and at a knee-adjacent location along the length of said leg, a now approved embodiment of the new protective pad is secured in an upper one of a plurality of different possible locations along said length.

Fig. 2 is an enlarged fragmentary front elevational view of a knee-adjacent portion of one of said trouser legs, with the pad now secured in a lower one of said possible locations along the leg length.

Fig. 3 shows said pad in rear elevation.

Fig. 4 is a horizontal section, taken on the line 4—4 of Fig. 2; this view being a collective one, in that the pad here is shown detached from the trouser leg.

Fig. 5 is a rear perspective view of the same pad as in Figs. 1-4, but also showing one of two strip members for constituting the carrying means aforesaid.

Fig. 6 is a view similar to Fig. 2, showing said two strip members in their fixed placements on a trouser leg; with the relative position of such a pad as that of Fig. 6 being merely indicated in dot and dash.

Fig. 7 is a horizontal section, taken on the line 7—7 of Fig. 6, with the pad of Fig. 6 now assumed to be actually present in the latter view.

Fig. 8 is a view similar to Fig. 2, but in perspective, showing a modification of said carrying means, and also indicating, in dot and dash, two possible locations for the upper end portion of a pad, such as the pad of Fig. 5.

Fig. 9 is a view similar to Fig. 3, but in perspective, showing the rear side of a pad like the pad illustrated in Figs. 2-7, but with the fastening instrumentalities carried by the pad shown in modified form.

Fig. 10 is a fragmentary detail section, taken on the line 10—10 of Fig. 9, with the pad shown as attached to a trousers leg by aid of the instrumentalities last named.

Fig. 11 is a view similar to Fig. 2, showing the front side of a pad modification, and also showing the fastening instrumentalities carried by the pad, said instrumentalities in a further modified form.

Fig. 12 is a fragmentary detail section, taken on the line 12—12 of Fig. 11.

Referring now to the drawings more in detail, and first to Figs. 1-4, here, as illustrative of any garment, men's, women's or children's, which it may be desired to have served by one or more knee protectors pursuant to the invention, there is shown in Fig. 1 a conventional pair of work trousers 15. One of the two legs of said trousers, these designated 16, is fragmentarily shown in Figs. 2 and 4; these leg portions being portions at the front of the trousers adjacent to the knee location.

The two pads 17 shown in Fig. 1 may be assumed to be alike; and, as best seen from Figs. 2-4, each pad is comprised of a rectangular sheet of a single material, with said sheet oblongovate in outline, and substantially all over of uniform thickness; said material, as already stated, being foam or sponge rubber or similar padding.

Permanently mounted on each pad 17, adjacent to each of its four rounded corners 18, is a snap fastener element 19. This fastening instrumentality 19 is preferably one of the socket type, and to meet all situations arising from possible severe separational strains relative to the snap fastener, each instrumentality 19 is one of a rather large size, as, for instance, one having its socket dimensioned to take the post portion of the coacting fastening instrumentality when the said post portion has a diameter of the order of one-quarter inch. Standard metallic snap fasteners are employed, for economy; and, as well known, the socket element of such a fastener is provided with a rod-like shank portion (20, Fig. 4), the latter at one end having a disk-like head (21, Fig. 4) and at its other end carrying the socket structure (22, Fig. 4).

As shown best in Fig. 4, such a head, this at

the outer side of the pad 17, is sunk well down in the body of the pad, this being made possible by the high compressibility of the pad material, and being consequent upon the fact that said rod-like shank portion is of a length much less than the normal thickness of the pad; thereby to set up a condition such that, with said socket structure clenched in the familiar way to said shank portion at its end remote from its said head, the latter will lie at the bottom of a fairly deep well-like depression (23, Fig. 4), in the outer side of the pad.

In order to insure that such well-like depressions will all persist at the outer side of the pad, 15 pad, a pair of tapes or strips 24, or full size tapes the same size or a little larger than the pad, of a somewhat flexible material yet one of considerably less limpness relative to easy flexure than the material of which the pad is made, are 20 secured to the pad at the rear thereof and along its two sides. These elements 24 perform satisfactorily when, for instance, they are made of a textile material such as duck or the like, but if desired, these elements 24 may be entirely 25 eliminated.

With the four fastening instrumentalities 19 secured to the pad, by way of suitable apertures in the pad and also by way of matching apertures in said strips or tapes, and by coupling 30 the metallic parts so that they are arranged as in Fig. 4 consequent upon the operation whereby a socket structure 22 is clenched to a shank portion 20, the flatwise face engagement of the strips 24 with considerable areas of the rear side of 35 the pad insures that the depressions 23 will be established and persist at the front side of the pad.

As a result, insurance is always had that, with a pad in use between the knee of a person and the ground, an instrumentality 19 may not transmit a sensible thrust against the knee; this for the reason that the pad must be compressed to an extent to cause virtual temporary disappearance of the depression 23 at said instrumentality before said thrust may be transmitted lengthwise of said instrumentality.

At the front of each trouser leg 16, the aforesaid coacting fastening instrumentalities, these designated 25, are permanently secured; suitably 50 spaced so that four of said instrumentalities 25 are couplable with the instrumentalities 19. With the latter socket-type snap fastener elements as above, said instrumentalities 25 are post-type snap fastener elements of corresponding size, having their posts (26, Fig. 4) outwardly directed relative to the front of a trouser leg. In the present case, six of the fastener elements 25 are shown as carried by each trouser leg 16; these elements so placed that when desired a pad 17 may be attached to said leg as shown in Fig. 1, that is, at a higher level, or as shown in Fig. 2, that is, at a lower level.

Referring to the modification illustrated in Figs. 5-7, the pad here illustrated, as indicated 65 by the use of the same reference numerals as in Figs. 1-4, is identical with the pad previously described; and the coacting fastening instrumentalities are also the same as above described. These snap fastener elements 25, however, instead of being secured directly to a trouser leg 16, are secured to a special carrying means. Said means is comprised of a pair of tapes or strips 27, or a piece of cloth the same size as the pad, which may be made of a sheet material such as 70 specified above for the tapes or strips 24. Said

strips 27 are coated on their rear sides with an adhesive of any of the well-known kinds rendered temporarily tacky or thermoplastic by application of a heated iron, thereby, and following cessation of the heat application and consequent setting of said adhesive to become permanently secured, as indicated in Fig. 7, to the outer front side of a trouser leg 16 at a selected placement along the length of said leg, or the strips 27 may be attached to the trouser legs 16 by stitching, stapling, or in any other manner. These strips 27 are herein shown, by way of example, as each carrying merely two of the snap fastener elements 25 or if a full size piece cloth is used, all four snap fasteners will be mounted 15 on that piece of cloth.

Fig. 8 illustrates a modification, in that for each trouser leg 16, the strips 28 provided, and corresponding to the strips 27, are of greater length and sufficiently so that each strip 28 may carry properly spaced therealong a great enough plurality of the snap fastener elements 25 to allow some only thereof to be used according as a pad 17 is at any time desired to be readily detachably placed at a higher level (as with its upper portion disposed as indicated at 17^a) or at a lower level (as with its upper portion disposed as indicated at 17^b) relative to the fixed placements of the strips 28. In the present case, by way of example, three of the elements 25 are shown as carried by each strip 28.

In the modification of Figs. 9 and 10, the same pad 17 again is shown, and pierced, also, near its four corners. Here, however, in each of said piercings is a metal rivet 29 having offset from its annular head 30 a tubular shank 31.

In order to establish at the outer side of the pad, at each of the four rivet locations, a well-like depression (23') for functioning as does a depression 23, the end of each of the rivet shanks 30 which is opposite to the rivet's annular head 30 is spread as shown at 32 in Fig. 10 to become headed over a metal washer 33. Such a washer is, on the one hand, of a sufficiently large diameter, and each rivet, on the other hand, is of sufficiently short length, to predetermine that a depression 23' will be of adequate depth, and, at the same time, to insure that an oppositely located depression, this at the back of the pad, will be established, as indicated at 34, to assist in obtaining a wholly protective burial of the hard metal parts within the pad.

Each of the four fastening instrumentalities carried by the pad is shown as of a familiar type of split-shank metal fastener 35. In Fig. 10 the halves of the shank of said fastener are marked 36, these extended from a disk-like head 37. With said head engaging the head 30 of the adjacent hollow rivet, and with said shank extending through said rivet, the free end portions of said shank halves may be piercingly advanced through the material of a trouser leg 16, and then spread, as shown in Fig. 10, cotter pin fashion. Desirably, a second washer 38 is employed at the location shown in Fig. 10.

In Figs. 11 and 12, a pad 17' is shown which is like the pads previously described, except that the pad 17' is substantially squarely rectangular, it is more elongate horizontally than vertically, and it is made of a single piece of sponge or foam rubber or similar padding material. The pad 17', near each of its four corners, has a slot 39 therethrough. Each of the four fastening instrumentalities carried by the pad, these also preferably of metal, incorporates a struc-

ture 40 at the outer end of which is a familiar type of spring-closed double-jaw clamp 41, with its jaws interpivoted as at 42, and with the upper jaw extended as a finger-piece 43 to be deliberately depressed when it is desired to release the clamp. The lower jaw is integral with a band-like tail piece 44 which, after being passed through one of the slots 39, is adapted to be finally bent as shown in Fig. 12, that is, to be bent on itself to establish a bight to pass through said slot, then further bent upwardly along a bottom length 45 to compress the material of the pad and so establish a knee-protective depression 46 at the back of the pad, and then terminally bent upward as at 47 to lock the structure 47 to the pad.

In applying the pad to a trouser leg 16, the material of the latter is pleatingly reversely folded on itself as illustrated, to present pleats 20 48, one for engagement by the two clamps 41 at one side of the pad and the other for engagement by the two clamps 41 at the other side of the pad, in the manner shown. The material used for the making of the structure 40 will have some reliency, as would be the case when, for instance, such material is half-soft spring brass; and, therefore, the bottom length 45 of a tail piece 44 will elastically swing upward when required, in coactive behavior relative to the protective function of the depression 46.

It is to be understood that the shape and size of the pads 17 may be altered as desired.

While I have illustrated and described the preferred embodiments of my invention, it is to be understood that I do not limit myself to the precise constructions and materials herein disclosed and the right is reserved to all changes and modifications coming within the scope of the invention as defined in the appended claims.

Having thus described my invention, what I claim as new, and desire to secure by United States Letters Patent is:

1. A knee cushioning and protective appliance for thus functioning when combined with a garment and when the wearer of such garment assumes a kneeling posture, said appliance comprising a slab-like pad of rubber of the kind stated, or a similar padding material, means for attaching the pad to a knee-adjacent portion of said garment at the exterior thereof, said means comprising a plurality of readily detachable fastening instrumentalities carried by the pad at spaced points along a line conforming substantially to the perimeter of the pad, said instrumentalities being so constituted as to be many times less compressible than the pad and incorporating elongate portions extending through the pad in substantially the direction of its thickness, and means associated with said instrumentalities and clenched to the pad in an arrangement such that at one side of the pad a well-like depression is established opposite to and surroundingly of lines of thrust from the ground along the lengths of said elongate portions.

2. A knee cushioning and protective appliance for thus functioning when combined with a garment and when the wearer of such garment assumes a kneeling posture, said appliance comprising a slab-like pad of rubber of the kind stated, or a similar padding material, means for attaching the pad to a knee-adjacent portion of said garment at the exterior thereof, said means comprising a plurality of readily detachable fastening instrumentalities carried by the pad at

spaced points along a line conforming substantially to the perimeter of the pad, said instrumentalities being so constituted as to be many times less compressible than the pad and incorporating elongate portions extending through the pad in substantially the direction of its thickness, and means associated with said instrumentalities and clenched to the pad in an arrangement such that at one side of the pad a well-like depression is established opposite to and surroundingly of lines of thrust from the ground along the lengths of said elongate portions, the means last-named including portions of said instrumentalities.

3. A knee cushioning and protective appliance for thus functioning when combined with a garment and when the wearer of such garment assumes a kneeling posture, said appliance comprising a slab-like pad of rubber of the kind stated, or a similar padding material, means for attaching the pad to a knee-adjacent portion of said garment at the exterior thereof, said means comprising a plurality of readily detachable fastening instrumentalities carried by the pad at spaced points along a line conforming substantially to the perimeter of the pad, said instrumentalities being so constituted as to be many times less compressible than the pad and incorporating elongate portions extending through the pad in substantially the direction of its thickness, and means associated with said instrumentalities and clenched to the pad in an arrangement such that at one side of the pad a well-like depression is established opposite to and surroundingly of lines of thrust from the ground along the lengths of said elongate portions, the means last-named including portions of said instrumentalities and sheet-like members made of a material less freely flexible than the pad, said members being at the back of the pad and arranged to cross said lines of thrust.

4. A knee cushioning and protective appliance for thus functioning when combined with a garment and when the wearer of such garment assumes a kneeling posture, said appliance comprising a slab-like pad of rubber of the kind stated, or similar padding material, means for attaching the pad to a knee-adjacent portion of said garment at the exterior thereof, said means comprising a plurality of readily detachable fastening instrumentalities carried by the pad at spaced points along a line conforming substantially to the perimeter of the pad, said instrumentalities being so constituted as to be many times less compressible than the pad and incorporating elongate portions extending through the pad in substantially the direction of its thickness, and means associated with said instrumentalities and clenched to the pad in an arrangement such that at one side of the pad a well-like depression is established opposite to and surroundingly of lines of thrust from the ground along the lengths of said elongate portions, the means last-named including portions of said instrumentalities and sheet-like members made of a material less freely flexible than the pad, said members being at the back of the pad and arranged to cross said lines of thrust, each of said instrumentalities being one of the cooperant elements of a snap fastener, these for coaction with the other elements of said snap fasteners where an appropriate set of the latter is carried by a knee-location portion of said garment at the exterior thereof.

5. A knee cushioning and protective appliance

for thus functioning when combined with a garment and when the wearer of such garment assumes a kneeling posture, said appliance comprising a slab-like pad of rubber of the kind stated, or similar padding material, means for attaching the pad to a knee-adjacent portion of said garment at the exterior thereof, said means comprising a plurality of readily detachable fastening instrumentalities carried by the pad at spaced points along a line conforming substantially to the perimeter of the pad, said instrumentalities being so constituted as to be many times less compressible than the pad and incorporating elongate portions extending through the pad in substantially the direction of its thickness, and means associated with said instrumentalities and clenched to the pad in an arrangement such that at one side of the pad a well-like depression is established opposite to and surroundingly of lines of thrust from the ground along the lengths of said elongate portions, the means last-named including portions of said instrumentalities and sheet-like members made of a material less freely flexible than the pad, said members being at the back of the pad and arranged to cross said lines of thrust, each of said instrumentalities being one of the cooperant elements of a snap fastener, these for coaction with the other elements of said snap fasteners where an appropriate set of the latter is carried by a knee-location portion of said garment at the exterior thereof, the first-named snap fastener elements being socket type ones, and the second-named snap fastener elements being post type ones.

6. A knee cushioning and protective appliance for thus functioning when combined with a garment and when the wearer of such garment assumes a kneeling posture, said appliance comprising a slab-like pad of rubber of the kind stated, or similar padding material, means for attaching the pad to a knee-adjacent portion of said garment at the exterior thereof, said means comprising a plurality of readily detachable fastening instrumentalities carried by the pad at spaced points along a line conforming substantially to the perimeter of the pad, said instrumentalities being so constituted as to be many times less compressible than the pad and incorporating elongate portions extending through the pad in substantially the direction of its thickness, and means associated with said instrumentalities and clenched to the pad in an arrangement such that at one side of the pad a well-like depression is established opposite to and surroundingly of lines of thrust from the ground along the lengths of said elongate portions, the means last-named including portions of said instrumentalities and sheet-like members made of a material less freely flexible than the pad, said members being at the back of the pad and arranged to cross said lines of thrust, each of said instrumentalities being one of the cooperant elements of a snap fastener, these for coaction with the other elements of said snap fasteners where an appropriate set of the latter is carried by a knee-location portion of said garment at the exterior thereof, there being a direct carrying means for said second-named snap fastener elements, said carrying means incorporating a plurality of strip-like sheet members or one sheet member the same size as said pad and carrying a plurality of said second-named snap fastener elements, said sheet members or sheet member being attached to a knee-location portion of said garment at the exterior thereof thereby to have

said garment portion permanently indirectly carry said second-named snap fastener elements, being coated, at their sides opposite to the sides thereof from which are projected the working ends of said second-named snap-fastener elements, with an adhesive to bond said sheet members or sheet member to said garment portion.

7. A knee cushioning and protective appliance for thus functioning when combined with a garment and when the wearer of such garment assumes a kneeling posture, said appliance comprising a slab-like pad of rubber of the kind stated or similar padding material, means for attaching the pad to a knee-adjacent portion of said garment at the exterior thereof, said means comprising a plurality of readily detachable fastening instrumentalities carried by the pad at spaced points along a line conforming substantially to the perimeter of the pad, said instrumentalities being so constituted as to be many times less compressible than the pad and incorporating elongate portions extending through the pad in substantially the direction of its thickness, and means associated with said instrumentalities and clenched to the pad in an arrangement such that at one side of the pad a well-like depression is established opposite to and surroundingly of lines of thrust from the ground along the lengths of said elongate portions, the means last-named including portions of said instrumentalities and sheet-like members made of a material less freely flexible than the pad, said members being at the back of the pad and arranged to cross said lines of thrust, each of said instrumentalities being one of the cooperant elements of a snap fastener, these for coaction with the other elements of said snap fasteners where an appropriate set of the latter is carried by a knee-location portion of said garment at the exterior thereof, there being a direct carrying means for said second-named snap fastener elements, said carrying means incorporating a plurality of strip-like sheet members or one sheet member the same size as said pad and carrying a plurality of said second-named snap fastener elements, said sheet members or sheet member being attached to a knee-location portion of said garment at the exterior thereof thereby to have said garment portion permanently indirectly carry said second-named snap fastener elements, being coated, at their sides opposite to the sides thereof from which are projected the working ends of said second-named snap fastener elements, with an adhesive to bond said sheet members or sheet member to said garment portion, the snap fastener elements carried by said sheet members or sheet member

5

10

being in a greater plurality than the total of snap fastener elements carried by the pad, and said elements carried by said sheet members or sheet member, being so spaced on the former that with said sheet members bonded to said garment portion one group of the last-named elements may be coupled to the elements carried by the pad to locate the latter at a higher level on said garment and another group of the elements carried by said sheet members or sheet member may be coupled to the elements carried by the pad to locate the latter at a lower level on said garment.

8. A knee cushioning and protective appliance for thus functioning when combined with a garment and when the wearer of such garment assumes a kneeling posture, comprising a slab-like pad of soft rubber or a similar padding material, and means for removably attaching the pad to a knee-adjacent portion of the garment at the exterior thereof, said removable attaching means comprising a plurality of fastening instrumentalities mounted on the back face of said pad, a sheet-like member, adhesive means securing said sheet-like member to the knee-adjacent portion of the garment, and a plurality of complementary fastening instrumentalities carried by said sheet-like member to be engaged by the fastening instrumentalities mounted on said pad.

9. A knee cushioning and protective appliance for thus functioning when combined with a garment and when the wearer of such garment assumes a kneeling posture, comprising a slab-like pad of soft rubber or a similar padding material, and means for removably attaching the pad to a knee-adjacent portion of the garment at the exterior thereof, said removable attaching means comprising a plurality of fastening instrumentalities mounted on the back face of said pad, a sheet-like member, adhesive means securing said sheet-like member to the knee-adjacent portion of the garment, and a plurality of complementary fastening instrumentalities carried by said sheet-like member to be engaged by the fastening instrumentalities mounted on said pad, said fastening instrumentalities being complementary snap fastener elements.
